UNITED STATES PATENT OFFICE.

DANIEL E. SOMES, OF WASHINGTON, DISTRICT OF COLUMBIA.

REFRIGERATOR-CAR.

SPECIFICATION forming part of Letters Patent No. 278,285, dated May 22, 1883.

Application filed January 24, 1883. (No model.)

To all whom it may concern:

Be it known that I, DANIEL E. SOMES, a citizen of the United States of America, residing at Washington, in the District of Columbia, 5 have invented certain new and useful Improvements in Refrigerator-Cars, of which the following is a specification, reference being had therein to the accompanying drawings.

The object of my invention is to furnish a comprehensive system of refrigerating and preserving fresh meats, fish, fruits, flowers, and other articles and substances that are liable to rapid decomposition or fermentation, and of storing, transporting, shipping, and 10 transferring such articles and substances without exposing them to an impure atmosphere, or to temperatures that can freeze or decompose them; and the invention consists in improved processes and improved mechanical 15 devices for extracting the heat from the articles to be preserved and conducting it to ice or other refrigerating material through metallic bars, posts, plates, hooks, and other metallic mediums.

20 It also consists in the combination and use of improved devices for excluding heat from inclosed chambers or spaces.

The invention further consists in improved 25 organized automatic mechanism for producing continuous circuits of air through and around ice and through a preserving-room, circulating around articles to be preserved, and conveying impurities arising therefrom and depositing them in the drip-water, to be carried off through the trap, as well as refrigerating said articles.

My invention further consists in the construction and application of automatic mechanism for the admission and exit of air.

The various devices and processes herein 30 described, and particularly pointed out and combined in the claims, are especially applicable to refrigerator cars, ships, store-houses, and other refrigerating structures. Air is a poor conductor of heat and cold, and when it constitutes a conducting medium between the articles refrigerated and the ice the process of 35 refrigerating is slow and imperfect when ice alone is used, the air being many degrees warmer than the ice, even in well-constructed 40 refrigerators now in use. To overcome this difficulty of bringing the temperature down to

a degree necessary to preserve fresh meats and fruits, salt has been used in connection with ice; but the process is expensive and unreliable, since the temperature is always fluctuating. Air-blasts forced by machinery alternately through the ice and against the articles refrigerated have been extensively used with and without salt; but the same objections named above hold good against this process. 55 Besides, it is more expensive, and the machinery is liable to break down or otherwise get out of order, involving the loss of whole car-loads and cargoes of valuable freight. Another serious objection is the fact that the 60 blasts of air cause rapid evaporation of the juices of the meats and fruits, and consequent loss of flavor, as well as loss of weight from shrinkage.

I will now proceed to describe my refrigerator car and store-houses, and the processes of 65 preserving perishable articles and substances therein.

Figure 1 is a plan view of the top or roof of a car. Fig. 2 is a vertical longitudinal section 70 of the car, on line $y y$ of Fig. 1. Fig. 3 is a plan view of the interior of the car with the top removed. Fig. 4 is an enlarged view of a swivel-hook and a section of a notched and 75 perforated bar on which the hook is hung. Fig. 5 is a side view of a hook without a swivel-joint. Fig. 6 represents a screen for protecting the open ends of the vertical pipes shown in Fig. 8. Fig. 7 shows an elbow of a pipe for connecting the vertical with the horizontal pipes. Fig. 8 is a perspective sectional view of a skeleton 80 of an ice-box constructed of metallic pipes with metallic bars placed between the pipes, the surrounding walls not shown. Fig. 9 is a sectional plan view of an ice-box, showing the top 85 ends of the vertical pipes and horizontal metallic bars connected to the metallic front wall of the ice-box, and the manner of attaching the bars thereto, and also a cross bar resting on horizontal bars. Fig. 10 represents a metallic 90 post sustaining a horizontal bar and bracing the front wall of the ice-box. Fig. 11 is a side view of a sleeper placed between the metallic pipes, which, together with the pipes, form the 95 grate of the ice-box. Fig. 12 represents a section of the front side of the metallic ice-box, with openings and doors at the lower part.

Fig. 13 shows a modification of my improved car or refrigerator, having an ice-box in one end only. Fig. 14 represents an automatic ventilator for the admission of outside air to the ice-box. Fig. 15 represents an ice box or room two or more stories high, and constructed of metallic pipes, with the casing and registers left off or not shown. Fig. 16 represents a row of these ice boxes or crates, constructed of metallic pipes with surrounding casings, and registers for regulating the volume of air that flows into the top openings and out of the bottom openings, and metallic beams which form connections between metallic boxes, and also serve as beams on which to hang meat. Fig. 17 represents a plan view of a store-house containing rows of metallic refrigerating-boxes, railway-tracks, and turn-tables. Fig. 18 represents a post and beam composed of wood and metal. Fig. 19 shows an end of a refrigerating store-house with doors for the admission and exit of cars. Fig. 20 is a side elevation of a store-house with openings for the admission of ice. Fig. 21 represents metallic receptacles of varying sizes, so selected and arranged as to completely fill a room or given space. Fig. 22 represents a scuttle in the top or roof of a car or other structure to admit ice and other articles. Fig. 23 is a detail plan view of a series of ice-boxes, *v*, connected by metallic beams *f*. Fig. 24 represents two perforated boxes, each being made so as to conform to the shape of a quarter of beef or lamb or other kind of meat. When the irregular sides of these boxes are placed together they form a rectangle or a square. Fig. 25 is a vertical section of one of the ice-boxes *v*, taken on line *x x*, Fig. 23, showing a non-conducting casing inclosing walls and grating, the said walls and grating being composed of metallic pipes.

The walls, roof, and floor of the car, building, or other structure are made double or multiple, with spaces between them, which are made air-tight. The walls, if not made of metal or lined with it, are lined with paper or cloth, which should be saturated with a strong solution of vitriol or copperas to prevent the fabric from rotting. The fabric may then be coated with copal, shellac, or other varnish, or paraffine, to make it air-tight and water-proof. The bottom of the spaces in the walls of the car and store-house and the spaces in the floors and roof are covered a quarter of an inch or so in depth with copal or other hard varnish, poured into them while warm. This varnish should be of a kind that will not become limpid or plastic by the heat of the sun. Before the varnish becomes cold, finely-powdered carbonate of lime or chalk, or plaster-of-paris, or soapstone is sifted upon it to make a solid foundation. The spaces above this foundation are filled with the substances above named, or with charcoal, or mixtures of the substances named. The side walls of the car constitute the two sides of the preserving-room *B*, and the end walls of the ice-boxes, while the front

walls, *D'*, Fig. 2, of the ice-boxes form the ends of the preserving-room. The walls *D'* are made of metal or of metallic frame with metal lining. The metallic beams *D²* are supported on metallic posts *D³* or on the front walls, *D'*. The ceiling *F* of the preserving-room is a few inches below the ceiling of the car, and its length is divided by a narrow central opening or flue from side to side. These two divisions of the ceilings *F* extend from the central opening to the ice-boxes and rest upon the front walls thereof, forming two flues, *G*, which conduct the air from the preserving-room through the central opening to the ice-boxes. A partition running through the central opening and extending below the ceiling *F* divides the said openings and the flues *G*. This will prevent back-drafts and eddies in the latter, and tend toward an equal division in the air as it leaves the preserving-room on its passage to the ice-boxes. The under sides of the ceilings *F* are preferably made to slope slightly toward the ice-boxes to facilitate the horizontal currents as they move toward the openings. In the lower part of the front wall, *D'*, of the ice-boxes are openings, to permit the air to pass freely from the ice-boxes to the preserving-room. These openings are provided with doors *d*, Fig. 12, for regulating the volume of air, and are made to slide vertically, or are hinged. The end walls of the car form the back walls of the ice-boxes, against which the vertical pipes *d* rest or lean. The vertical pipes connect with the horizontal pipes, which form the grate of the ice-box, and are intended to come in contact with the ice and to conduct and refrigerate such air as fails to find its way easily through the mass of ice in the ice-boxes when the ice is too densely packed. The moisture in the air is condensed to water as it passes through these cold pipes, and, in the form of drops or small streams, discharges itself through the open ends of the horizontal pipes, or through holes in the under side of said pipes, and makes its way to the trap and is carried off with the drip-water. The bars *E²* are interposed between the horizontal pipes, in this instance, as shown, which serve to help sustain the ice and to receive most of its blow as it is dropped into the ice-box, the bars being higher than the pipes. The bars have notches *n*, as shown, which grasp the sills of the ice-boxes and hold them in place. Beneath the grate is a deflector, *a*, sloping toward the preserving-room, to facilitate the movement of the air-current and direct the drip-water to a gutter, *a'*, near the lower edge of the deflector. The gutter is made to extend the whole length of the grate and to incline toward one end, or from each end toward the center of the deflector, where it meets the trap which conducts the drip-water to the outside of the car. Metallic pipes *E*, Fig. 8, and bars *E²*, that form the grate, stretch from sill to sill of the ice-boxes transversely over the deflector and gutter, the pipes uniting with the verti-

cal pipes that extend up the back wall of the ice-box.

It is important to make the car as nearly as possible air-tight, in order to prevent the escape and waste of cold air and the admission of warm air. I therefore prefer to have the interior and also the spaces lined with sheet metal, or the latter may be lined, as herein already set forth. All the joints of the scuttles and doors are made tight by means of rubber tubes or strips, preferably with black rubber. The exterior of the car should have a thick coating of white-lead or zinc paint. The lead or zinc paint should be pure and mixed with bleached linseed-oil, and all the joints and interstices of the walls puttied up with putty, preferably of the same material. After the paint is thoroughly dried, two or three coats of coach-varnish should be applied. This coating, being white, will mitigate the effects of the sun upon the car, and will also exclude any warm air that might otherwise find its way into the air-spaces or the interior. The varnish will prevent the adhesion of cinders and dust, and the small quantity that may find temporary lodgment will be quickly removed by wind and rain. The preserving-room is used for the transportation or storage of fresh meats. The carcasses or quarters are hung upon the hooks, which are movable and held in place by the notches or pins. The spaces on the floor beneath the suspended quarters are utilized by perforated metallic receptacles, in which are packed cut meats, fruits, poultry, eggs, and other articles. These receptacles are made of any convenient shape, and while they may vary in size, their dimensions are such that when packed side by side in rows, if properly selected, will completely fill the spaces between the sides and ends of the preserving-room or any given space, which prevents displacement in starting or stopping the car. Fig. 21 represents a space nine feet long filled with these receptacles of varied sizes, as indicated by figures. These receptacles, being perforated so that the perforations register with each other, will readily permit currents of air to pass through them and from one to another when the sides of the boxes are in close contact, and, being made of metal and connected with other metal conductors which lead to and are in contact with the refrigerant, must rapidly conduct the heat from the contents of the receptacles and refrigerate and preserve them from fermentation and decomposition. When only a section of a car is used a partition is easily erected and made removable, to be used at pleasure. The said receptacles, as well as the bars, posts, and such other metallic conductors as are liable to come in contact with articles of food, are nickel-plated or tinned, while the metal that comes in contact with ice may be galvanized. The said receptacles or the material of which they are made should have a coat of nickel or tin after the openings or perforations have been made.

This coating will prevent corrosion and will not deleteriously affect the food.

Fig. 15 represents the interior walls of an ice box or room one and two stories high constructed of metallic pipes. The outside pipes constitute the first story, supported on a platform of timbers, under which an air-chamber is formed. The pipes have elbows attached to their upper and lower ends. The upper 75 elbows project outwardly through a band or beam of wood or metal that surrounds the walls of pipes, while the lower elbows connect with horizontal metallic pipes that extend across the timbers above the floor. 80

The manner of constructing the walls is as follows: After the first side is put up, as above described, the opposite side should follow with the horizontal pipes arranged between the horizontal pipes connecting the vertical pipes of the first side. The horizontal pipes connected with the vertical pipes of the third and fourth sides extend transversely across and above those of the first and second, thus forming two tiers of grate-bars for the ice to rest upon, while the spaces between the bars permit currents of air to flow through them on their way from the mass of ice to the preserving-room. When this refrigerating apparatus is two stories or more high the second story is constructed in the same manner, being inside the first, and the third inside the second, and so on, with the pipes of the outer walls sufficiently far apart to permit the elbows of the inner pipes to project beyond the outer walls. By this arrangement the metallic conductors are multiplied and cooling-surface increased. V V V, Fig. 16, represent a series of these metallic pipe-boxes, with non-conducting casings having registers v' v^4 for regulating the currents of air, (the pipes not shown.) These registers are attached to air-chambers v^2 , which inclose the ends of the pipes, and also openings into the interior of the ice-box. On opening the upper and lower registers, v' v^4 , currents of air flow from the upper air-chamber, v^2 , down through the vertical and through horizontal pipes, and out from the bottom air-chamber, v^2 , through the lower registers, v^4 , as indicated by the arrows. Other currents of air enter the interior of the ice-boxes v from the same upper air-chamber, v^2 , through spaces between the vertical pipes, and pass through the mass of ice and the grating into a chamber below the grating and through the registers v^4 . The ice-boxes have registers in their tops, also for the admission of air to the interior of the boxes, when large lots of warm meat received into the refrigerator store-house make it necessary to accelerate refrigeration therein. The metallic beams f , Fig. 16, are inserted through holes f' , and come in contact with the refrigerant, or with metal which is in contact with the refrigerant, and form connections between the different ice-boxes as good conductors of heat and cold, so that when meat or other articles are in contact with said beams, or with hooks,

links, rings, or the like, which are in contact with said beams, the heat which the articles contain will be rapidly conducted to the refrigerant. In some cases, however, it will be convenient to use one box only, with the outer ends of the beams supported on a post, D³, Fig. 16.

Fig. 17 is a plan view of a store-house divided into two refrigerator and preserving rooms, with non-conducting walls and doors between them, the outer room being intended for storage of such articles as do not require the lowest preserving-temperature. The partition-wall serves to protect the inner store-room from immediate contact with the outside air or heat, the outer doors being closed before the inner ones are opened. This store-house contains a series of ice-boxes, v, connected by metallic beams f, the ice-boxes D, and preserving-rooms B B', herein described; also, railway-tracks O² and turn-tables O', for the conveyance of articles liable to ferment or decompose from the action of heat or cold or from an impure atmosphere.

W', Fig. 19, is an end view of a store-house showing a section of multiple walls, with bolts P to stay the walls, and also doors u for the admission of cars on a railway-track. (Shown in Fig. 17.)

W², Fig. 20, is a section of one side of a store-house with multiple walls and spaces, the latter being filled with non-conducting material, and openings b² for the introduction of ice.

A A, Fig. 18, respectively represent a compound metallic and wooden post and a compound metallic and wooden beam, when posts and beams of unusual strength are needed. The metallic parts come in contact with ice or with metal in contact with ice. The openings or scuttles b, Fig. 1, in the roof are for the admission of ice, though openings in the walls may be substituted. The scuttles b' are designed for the admission of articles to be preserved when they are found more convenient than side doors of the car. The casings C' of the openings have outwardly-projecting seats b⁶, which are made to fit tightly to the top of the roof. The lower edges of the casings extend below the roof, and the upper edges above the projecting seats b⁶. The removable covers b³ are provided with downwardly-projecting flanges b⁴, which surround the upwardly-projecting edges above the seats and fit the seats tightly. An interior cover, b⁵, below the top one, is tightly fitted to seats which project inwardly from the casing. This device protects the interior of the car from the introduction of air, dust, and storm.

Fig. 14 represents an automatic ventilator which embodies an air-duct, P, screens P² at the upper portion of the duct, and a valve, R, hung on trunnions or axes, and operates in an enlarged portion of the air-duct when the upper or lower end of the duct is necessarily small. The valve is not attached on a central line to the trunnions, but is intentionally

smaller on the side of the trunnions than on the other; but the smaller side is thicker or is weighted so as to be somewhat heavier than the larger side. A rest or seat projects from the inside of the walls of the duct on a level with the upper surface of the valve, to prevent the larger side from rising above a common level, while another seat projects from the opposite wall of the duct on a level with the lower surface of the valve, to prevent the smaller side from falling below a common level. The object of this device is to cause the air from without to automatically enter the ice-box or some other desirable part of the refrigerator or car whenever a partial vacuum in the interior is caused by condensation or from other cause, and also to prevent the air from flowing outwardly through the same channel. When this apparatus is used in connection with a passenger-car or building or other structure requiring an outward current of air, an additional duct may be supplied, with the seat S' placed above the valve, the larger portion of the valve being heavier than the smaller portion, but having no seat or stop above it. This arrangement permits an upward and outward current of air. As heat expands and cold contracts the volume of air, a partial vacuum is produced in an air-tight car or room by the falling temperature; hence I have applied this automatic mechanism in order to have a full supply of air in the preserving-room and ice-box, and at the same time prevent an outward flow and loss of cold air. In this case the ventilator is located in or over the ice-box, to admit the air directly upon the ice, where it is refrigerated before it enters the preserving-room. It may, however, be placed at any convenient point by having a pipe to conduct the air to the ice-box.

When the boxes are charged for the first time, the ice in contact with the body of iron or other metal melts more rapidly and causes the temperature to fall many degrees lower than when it is in contact with wood and other poor conductors of heat and cold; but when the temperature has fallen to within one or two degrees, of the freezing-point it will remain at that point, with the consumption of a smaller quantity of ice than when the temperature stands at any higher degree, even when the ice covering the metal is only a few inches thick; hence I am enabled by means of the devices and processes herein described to reduce the temperature in a refrigerator to a degree where evaporation substantially ceases, and fermentation and decomposition are prevented, whereby fresh meats, fresh fish, fruits, and the like are preserved for many months with their natural juices and flavor held intact. The difference in weight between metal and wood may suggest an objection to the application of the devices herein described to cars and ships; but when the size is taken into account, and the important fact that a much smaller quantity of ice is required to be car-

ried to produce not only as good results, but better, the objection proves groundless. Furthermore, I have provided beams, posts, bars, and the like, as shown in Fig. 18, which are 5 made of wood and metal so combined that the metallic portions are in contact with ice or with metallic articles in contact with ice, while the wooden portions serve as supports.

Having thus described my invention, what I 10 claim as new, and desire to secure by Letters Patent, is—

1. A refrigerator - car provided with a metallic ice-box having a metallic grate, an inclosed cooling or preserving room having a 15 ceiling below the ceiling of the car and above the front side of the ice-box, forming a flue between the said ceilings extending to an opening at the opposite end of the preserving-room, and an opening in the front side, below the ice- 20 grate, substantially as and for the purpose set forth.

2. A refrigerator - car provided with a metallic ice - box, a metallic grate, an inclosed cooling or preserving room having a central 25 transverse opening in its ceiling, flues between said ceiling and the ceiling of the car, metallic beams connected with the ice-box, and metallic hooks or links connected with the beams, substantially as and for the purpose set forth.

3. In a refrigerating apparatus, an ice - box 30 having its grate constructed of hollow metallic bars, and solid metallic bars interposed between said hollow bars, substantially as and for the purpose set forth.

4. In a refrigerating apparatus, an ice - box 35 having its grate constructed of hollow metallic bars and solid metallic bars alternately arranged, vertical hollow bars connected with said hollow grate-bars, an upper opening and a lower opening for the admission and exit of air, and means for regulating the volume of air, substantially as and for the purpose set forth.

5. In a refrigerating apparatus, an ice box 40 or room having its walls constructed of metallic pipes connected with horizontal pipes, which form the grate of the ice-box, a casing surrounding said pipes, with openings for the admission and exit of air, and means for regulating it, substantially as and for the purpose set forth.

6. A series of refrigerator-boxes having their 45 walls and grates constructed of metallic pipes surrounding non-conducting casings provided with air-openings at their upper and lower parts, means for regulating the air above and below the grates, metallic beams with their ends in contact with the metallic walls of the ice-boxes, said boxes being separated one from another, substantially as and for the purpose set forth.

7. A refrigerator store-house containing 50 ice-boxes, preserving - rooms, railway-tracks, a transverse partition, and doors dividing the store-house into two refrigerator-apartments, so that the outer doors of the store-house may

be closed before the doors between the apartments are opened on the admission or exit of refrigerator-cars, substantially as and for the purpose set forth.

8. A store-house constructed with non-conducting walls and roof, a series of metallic refrigerator-boxes, constructed and arranged, substantially as herein described, within said store-house, metallic beams in contact with the metallic walls of the ice-boxes, railway-tracks, and turn-tables within said store-house, substantially as and for the purpose set forth.

9. A store-house constructed with non-conducting walls, roof, and floor, a series of metallic refrigerator-boxes and preserving-rooms provided with metallic beams extending from the interior of said refrigerator-boxes into the preserving-rooms, metallic hooks or their equivalents in contact with said beams, safes with in said store-house for storing and preserving articles liable to be injuriously affected by heat or frost, and railway-tracks and turn-tables within said store-house, substantially as and for the purpose set forth.

10. In a refrigerator, a preserving-room with non-conducting walls, floor, and roof, metallic posts D^3 , longitudinal metallic beams D^2 , and cross-beams K , in combination with flues $G G$ and ice-boxes $D D$, provided with vertical and horizontal air-pipes, substantially as and for the purpose set forth.

11. In a refrigerator, an ice-box having vertical metallic air-pipes d , which line the non-conducting walls of the ice-box, horizontal metallic pipes and bars constituting the ice-grate, openings in the walls of the ice-box above and below the grate for receiving and discharging air-currents, and means for regulating the exit-currents, substantially as and for the purpose set forth.

12. In an ice-box, the combination of vertical and horizontal metallic pipes connected together, an air-chamber below said pipes, a non-conducting inclosing-casing, a belt or beam surrounding the pipes, having openings to receive the upper ends of said pipes and openings for admitting air to the mass of ice, substantially as and for the purpose set forth.

13. In an ice-box, the combination of the non-conducting outer walls, Q , inner walls, d , composed of metallic pipes, the belt Q^2 for staying said pipes, and having apertures for air-currents, the air-chamber v^2 , and the registers v^4 , substantially as and for the purpose set forth.

14. In a refrigerator, an ice-box having hollow metallic grate-bars provided with apertures in their lower sides for the exit of air and condensed vapors, substantially as and for the purpose set forth.

15. In a refrigerator, a deflector, a , having a gutter, a' , integral therewith, arranged on the floor of the refrigerator, for directing air-currents into the preserving-room and conducting the drip-water to the trap, substantially as and for the purpose set forth.

16. An improvement in linings for double or multiple walls, roofs, or floors, consisting of a textile fabric having been saturated with a solution of copperas and coated with paraffine, substantially as and for the purpose set forth. 5
17. An improvement in linings for double or multiple walls, roofs, or floors, consisting of a textile fabric having been saturated with a solution of copperas, substantially as and for the purpose set forth. 10
18. An improvement in linings for walls, roofs, and floors, consisting of paper having been saturated with a solution of copperas, substantially as and for the purpose set forth. 15
19. An improvement in linings for walls, roofs, and floors, consisting of paper having been saturated with a solution of copperas and varnished, substantially as and for the purpose set forth. 20
20. An improvement in linings for walls, roofs, and floors, consisting of a textile fabric having been saturated with a solution of copperas and varnished, substantially as and for the purpose set forth. 25
21. An improvement in linings for walls, roofs, and floors, consisting of paper having been saturated with a solution of copperas and coated with paraffine, substantially as and for the purpose set forth. 30
22. An improvement in packing for spaces between walls, floors, and roofs of refrigerator-structures, consisting of a thin layer of varnish and powdered chalk at the bottom of said spaces and chalk above said layer, substantially as and for the purpose set forth. 35
23. An improvement for packing for spaces between walls, floors, and roofs of refrigerator-structures, consisting of a thin layer of varnish and powdered chalk at the bottom of said spaces and powdered charcoal above said layer, substantially as and for the purpose set forth. 40
24. An improvement in packing for spaces in walls, floors, and roofs of refrigerator-structures, consisting of a thin layer of varnish and chalk at the bottom of the spaces and a mixture of chalk and charcoal above said layer, substantially as and for the purpose set forth. 45
25. An improvement in packing for spaces in walls, floors, and roofs of refrigerator-structures, consisting of a thin layer of varnish and soapstone at the bottom of said spaces and powdered charcoal above said layer, substantially as and for the purpose set forth. 50
26. An improvement in packing for spaces in walls, floors, and roofs of refrigerator-structures, consisting of a thin layer of varnish and plaster-of-paris at the bottom of said spaces and a mixture of charcoal and chalk above said layer, substantially as and for the purpose set forth. 55
27. An improvement in packing for spaces in walls, floors, and roofs of refrigerator-structures, consisting of a thin layer of varnish, chalk, and soapstone at the bottom of said 60
- spaces and a mixture of chalk and charcoal above said layer, substantially as and for the purpose set forth. 65
28. A refrigerator-car having non-conducting walls and roof provided with coatings of white paint and varnish applied to the exterior of said walls and roof, whereby the heat of the sun is mitigated, the surface of the car made impervious to water and air, and the friction of the atmosphere lessened when the car is in motion, substantially as and for the purpose set forth. 70
29. An improvement in a scuttle in the roof of a car or deck of a vessel, consisting of a casting, C', which surrounds the openings b', a seat, b⁶, a removable cover or lid, b³, having a flange, b⁴, and an interior lid, b⁵, and its supporting seat, substantially as and for the purpose set forth. 80
30. An automatic ventilator having a horizontal valve with journals which turn in bearings arranged aside from the central line of the valve, leaving a larger portion of the valve on one side of the journals or bearings than on the opposite side, in combination with an air-duct, substantially as and for the purpose set forth. 85
31. An automatic ventilator having an air-duct and a valve with its journals arranged aside from its central line, leaving a larger portion of the valve on one side of the journals than on the other, the smaller portion being slightly heavier than the larger portion, and provided with a seat to prevent it from falling below a common level, while the larger portion of the valve is free to fall and the smaller to rise whenever there is a greater air-pressure downward than upward within the air-duct, whereby the valve is opened for the admission of air and automatically closed by the heavier portion falling to its seat when the vacuum is filled, substantially as and for the purpose set forth. 90
32. In a ventilator, the automatic valve R, in combination with the enlarged portion of the air-duct P and seat S', substantially as and for the purpose set forth. 95
33. In a ventilator, the automatic valve R, in combination with the enlarged portion of the air-duct P and the screens P² P², substantially as and for the purpose set forth. 100
34. Receptacles having openings in their walls, said openings being arranged so as to register with each other when the sides of the receptacles are in close contact, substantially as and for the purpose set forth. 105
35. Receptacles having openings in their tops and bottoms, said openings being made so as to register with each other when the top of one receptacle is in close contact with the bottom of another, substantially as and for the purpose set forth. 110
36. Nickel-plated metallic receptacles having perforated walls, said perforations being arranged so as to register with each other 115
- 120

when the sides of the receptacles are in close contact, substantially as and for the purpose set forth.

37. Nickel-plated metallic receptacles having perforated tops and bottoms, said perforations being made so as to register with each other when the top of one receptacle is in close contact with the bottom of another, substantially as and for the purpose set forth.

38. Nickel-plated metallic receptacles having perforated walls, tops, and bottoms, said perforations being made so as to register with each other when the sides of the receptacles are in close contact and the top of one receptacle is in contact with the bottom of another, substantially as and for the purpose set forth.

39. An improvement in supports for suspended fresh meats, consisting of nickel-plated hooks, links, or rings, in combination with nickel-plated bars in contact with a re-

frigerant, substantially as and for the purpose set forth.

40. An improvement in supports for suspended meats and other articles of food which contain moisture, consisting of metallic bars or beams and posts plated with nickel, substantially as and for the purpose set forth.

41. An improvement in supports for suspended meats and other articles requiring refrigeration, nickel-plated hooks or links or their equivalent, in combination with metallic bars, pipes, posts, or other metallic material in contact with a refrigerant, substantially as and for the purpose set forth.

In testimony whereof I affix my signature in presence of two witnesses.

DANIEL E. SOMES.

Witnesses:

F. C. SOMES,
M. HENRY.
